UNITED STATES PATENT OFFICE

159,834

COMBINED GLOVE HOLDER AND HANDBAG SUPPORT

Louis G. Meyers, New York, N. Y., assignor to Klik Enterprises, Inc., a corporation of Delaware

Application April 11, 1950, Serial No. 9,127

Term of patent 14 years

(Cl. D87—2)

To all whom it may concern:

Be it known that I, Louis G. Meyers, a citizen of the United States of America, residing at New York, in the county of New York and State of New York, have invented a new, original, and ornamental Design for a Combined Glove Holder and Handbag Support, of which the following is a specification, reference being had to the accompanying drawing, forming a part hereof.

In the drawing:

Figure 1 is a side elevational view of a combined glove holder and handbag support, embodying my new design, and

I claim:

The ornamental design for a combined glove holder and handbag support, as shown.

LOUIS G. MEYERS.
